UNITED STATES PATENT OFFICE.

LOUIS CARLETON BULKLEY, OF ALDEN BRIDGE, LOUISIANA.

APPARATUS FOR COATING COTTON-SEEDS AND THE LIKE.

No. 908,443.

Specification of Letters Patent.

Patented Jan. 5, 1909.

Application filed August 10, 1906. Serial No. 329,985.

To all whom it may concern:

Be it known that I, LOUIS CARLETON BULKLEY, a citizen of the United States, residing at Alden Bridge, in the parish of 5 Bossier and State of Louisiana, have invented certain new and useful Improvements in Apparatus for Coating Cotton-Seeds and the Like, of which the following is a full, clear, and exact specification.

10 This invention relates to improvements in an apparatus for coating cotton seed and the like, and the object of the same is to provide an improved cheap and efficient apparatus for producing this result.

15 To the attainment of this end and the accomplishment of other new and useful objects, as will appear, this invention consists in the features of novelty hereinafter more fully described and claimed, and shown in 20 the accompanying drawing illustrating an exemplification of the invention, and in which—

Figure 1 is a side elevation, partly in longitudinal section, of a machine constructed 25 in accordance with the principles of this invention; Fig. 2 is a front elevation of Fig. 1; Fig. 3 is an enlarged detail sectional view of a portion of the cylinders and cover showing the manner of securing the cover and cylinders in position.

30 Referring more particularly to the drawing, and in which the same reference characters designate similar parts throughout the several views, the numerals 10—11 designate 35 respectively front and rear standards; 12—13, upper and lower connecting bars, and 14, braces extending respectively from the standards to the cross-bars to brace the same, the whole being constructed of any suitable material, preferably metal, to form a supporting frame. The upper ends of the standards 10—11 preferably project for some distance above the bars 12, and journaled at the top of each of the front standards 10 is a grooved 40 pulley or roller 15, and similarly supported by the upper ends of the rear standards 11 are rollers or pulleys 16, which have extended bearing surfaces, and are arranged longitudinally of the frame.

45 The numeral 17 designates a cylinder having a bottom 18 and constructed of any suitable material, preferably metal. Extending from the edge of the open end of this cylinder are any suitable number of lugs or projections 19, preferably in the shape of pins having threaded extremities.

A second cylinder having a reticulated body portion 20, a bottom 21, and a circumferential ring 22, at the open end, is placed within the first cylinder 17, so that the bottom 21 will rest against the bottom 18, and the outer edge of the ring 22 will be flush with the open end of the cylinder 17. This second cylinder is of a diameter somewhat smaller than the diameter of the first cylinder to form a space therebetween, and projecting from the edge of the ring 22 are lugs or projections 23, similar to the lugs or projections 19 (see Fig. 2).

50 A third cylinder having a reticulated body portion 24, of a coarser mesh than the second cylinder, is placed within the second cylinder, so that its bottom 25 will engage and rest against the bottom 21. This cylinder is provided with an annular ring 26 surrounding the edge of the cylinder, and is also provided with lugs or projections 27, similar to the lugs or projections 19—23, which extend beyond the edge of the rings, and said cylinder is of a diameter smaller than the 55 diameter of the second cylinder to form an intervening space. The edges of the rings 22 and 26 are flush with each other and with the edge of the outer cylinder 17, and resting against and engaging all of these edges is a 60 suitable cover or closure 28 which, if desired, may be provided with a circumferential flange 29 which extends into the space between the ring 22 and the outer cylinder 20 and disposed between the cover and the edge 65 of the outer cylinder is a suitable gasket 30. The periphery 31 of the cover projects beyond the periphery of the outer cylinder 20, and provided in the cover adjacent the inner cylinder is a suitable opening or hand-hole 70 32 which is closed by a suitable closure 33, pivotally supported as at 34 to the cover, and held in position by any suitable fastening or securing means 35. The projections or lugs 19 on the outer cylinder are adapted to pass 75 through the cover 28, for supporting the cover in position, and mounted on the projecting threaded extremities thereof are thumb nuts 36 which clamp and hold the cover against displacement. The lugs or 80 projections 27—23 respectively on the inner and intermediate cylinders pass through the cover in a similar manner, and are engaged by thumb-nuts 37—38 which serve as means for supporting and holding these cylinders 85 in position. Thus assembled, the cylinders are placed upon the rollers 15 and 16 on the 90

supporting frame with the end of the cylinder adjacent the bottom resting upon the rollers 16, and the projecting periphery 31 of the cover resting in the grooves in the rollers 15, which serves as a means for preventing displacement of the cylinders. The rollers 16 are of a width to form an extended support for the cylinder from the bottom to a point beyond the bottom 25 of the innermost cylinder.

Projecting from the cover 28 is an operating handle 39. Removably supported by the framework, preferably by the cross-bars 13, beneath and in close proximity to the cylinders is a pan or receptacle 40 of any desired shape and of a size preferably somewhat larger than the diameter of the cylinders, to receive the material therefrom in a manner to be set forth.

With the parts thus assembled, the seed to be treated are inserted into the inner cylinder through the hand-hole 32, together with sufficient quantity of a thin paste of any quick setting cement, such as plaster of paris, or the like; enough of which is used to thoroughly moisten all of the seeds. After the closure 33 has been secured in position, the cylinders are revolved upon their supports by means of the handle 39, until the seeds are thoroughly wet and covered with this coating. Any suitable dry material is then inserted through the hand-hole and the cylinders again revolved. Sufficient of this dry material should be used to absorb all of the superfluous moisture. When the moisture has been absorbed, the cylinders are taken off of the support and the thumb-nuts 38 removed, which will permit the two inner cylinders supported by the cover 28 to be removed from the outer cylinder. These two cylinders are again placed upon the supporting rollers 15-16, and revolved in a similar manner. During this revolution the superfluous material will fall out through the mesh of the reticulated material 20, and into the pan or receptacle 40. After all of this material has been removed, the cylinders are again taken from the support, the thumb-nuts 38 removed, and the inner cylinder taken out of the intermediate cylinder, and with the cover 28 is again replaced upon the support, after the pan or receptacle 40 has been emptied of its contents. A rotation of this cylinder will cause the cotton seed to pass through the mesh and fall into the pan or receptacle 40. Obviously, any coloring pigment may be used in the coating solution to designate one kind or grade of seed from another, and fertilizer may also be added to stimulate the first growth. If the seed should stick together they may be placed in the cylinder when dry, when tumbling motion caused by the revolution of the cylinder will separate them. Seed thus treated and coated may be planted from an ordinary

corn, pea, or bean planter, or check-row corn planter, provided with a suitable drop-plate through which the seed will pass, thereby obviating the necessity of chopping out the plants or wasting the seed. It will be noted that the flange 31 on the cover 28 serves as a guide for each of the cylinders, and that the rollers 16 are of a sufficient width to successively receive and support the ends of the various cylinders.

In order that the invention might be fully understood, the details of an embodiment thereof have been thus specifically described, but

What I claim is:

1. A device of the class described, containing an outer rotatable receptacle, a closure for the receptacle, a reticulated receptacle within the first said receptacle, also adapted to be closed by the closure of the first receptacle, and means for securing said reticulated receptacle to the closure and for holding said reticulated receptacle stationary with relation to the outer receptacle.

2. A device of the class described, containing an imperforate rotatable outer receptacle, a closure removably secured to said receptacle, a reticulated receptacle within and spaced from the imperforate receptacle, and means for removably securing the reticulated receptacle to the closure, said closure serving to close and support the reticulated receptacle within the outer receptacle and stationary with relation thereto.

3. A device of the class described, containing an imperforate rotatable receptacle, a closure for the receptacle, means for removably securing said closure to the receptacle, a plurality of reticulated receptacles within the first imperforate receptacle, arranged one within the other stationary with relation to the imperforate receptacle and with respect to each other, and means for removably securing said reticulated receptacle to the closure, said closure serving to support and close the reticulated receptacles, and all of said receptacles being spaced from each other.

4. A device of the class described, containing a plurality of receptacles arranged within and spaced from each other, said receptacles being stationary with respect to each other and rotatable about a common axis, a common closure for said receptacles, means for securing the closure to one of the receptacles, and means on the other receptacles removably engaging the closures whereby said closure will form a support for the last said receptacles.

5. A device of the class described, containing a receptacle, a closure for the receptacle, projections on the receptacle adapted to pass through the closure, means engaging said projections on the outside of the closure for securing the latter in position, a reticulated receptacle within the first receptacle,

projections on said reticulated receptacle passing through the closure, and fastening means engaging said projections on the outside of the closure, said closure serving to support and close said reticulated receptacle.

6. A device of the class described, containing a receptacle, a closure for the receptacle, threaded projections extending from the edge of the receptacle and passing through the closure, nuts engaging the projections on the outside of the closure for securing the latter in position, a reticulated receptacle within and spaced from the first receptacle, the end of said reticulated receptacle resting against the closure, threaded projections extending from the said end and passing through the closure, and nuts engaging the extremities of the projections for securing the reticulated receptacle in position, said closure serving to support and close the reticulated receptacle.

7. A device of the class described, containing a plurality of concentric receptacles spaced from each other, the inner receptacles having reticulated bodies, the bottom of all of the receptacles resting respectively against each other, a common closure for the receptacles, said closure resting against the open ends of the receptacles, means for removably securing the closure to the outer receptacle, and means for removably securing the inner receptacle to the closure, said closure serving to close and support the inner receptacles and hold the bottoms thereof respectively in contact.

8. In a device of the class described, the combination of a supporting frame, a receptacle removably and rotatably mounted upon the frame, a closure for the receptacle, and a receptacle within the first receptacle supported and closed by the closure of the first receptacle, the second said receptacle being adapted to be removed from the first receptacle and replaced upon the frame.

45 9. In a device of the class described, the combination of a frame, supporting rollers journaled therein, a receptacle supported on the rollers, a closure for the receptacle, and a receptacle within the first receptacle supported and closed by the closure of the first receptacle, the second said receptacle being adapted to be removed from the first receptacle and replaced on the rollers, one of said rollers engaging the first receptacle adjacent the bottom and being of a width to receive and support the lower edge of the second said receptacle when removed from the first cylinder.

10. In a device of the class described, the

combination of a frame, supporting rollers 60 journaled therein, a receptacle supported on the rollers, a closure for the receptacle, a receptacle within the first receptacle supported and closed by the closure of the first receptacle, the second said receptacle being adapted to be removed from the first receptacle and replaced on the rollers, one of said rollers 65 engaging the first receptacle adjacent the bottom and being of a width to receive and support the lower edge of the second said 70 receptacle when removed from the first receptacle, and a receptacle supported below the first said receptacles.

11. In a device of the class described, the combination of a frame, supporting rollers 75 journaled therein, one set of said rollers being grooved, a receptacle, a closure for the receptacle removably secured thereto, said closure extending beyond the periphery of the receptacle to form a circumferential flange adapted 80 to enter the groove in the rollers, the free end of the receptacle resting upon the other rollers, and a second receptacle within the first receptacle supported and closed by the said closure, the said second receptacle being 85 adapted to be removed from the first receptacle and replaced upon the frame with the flange on the closure resting in the grooved rollers and with its free end engaging and supported by the said other rollers. 90

12. In a device of the class described, the combination of a frame, supporting rollers journaled therein, one set of said rollers being grooved, a receptacle, a closure for the receptacle removably secured thereto, said closure 95 extending beyond the periphery of the receptacle to form a circumferential flange adapted to enter the groove in the rollers, the free end of the receptacle resting upon the other rollers, a second receptacle within the 100 first receptacle supported and closed by the said closure, the said second receptacle being adapted to be removed from the first receptacle and replaced upon the frame with the flange on the closure resting in the grooved 105 rollers, and with its free end engaging and supported by the said other rollers, said closure being provided with an opening communicating with the said second receptacle, and a closure for said opening. 110

In testimony whereof I have signed my name to this specification, in the presence of two subscribing witnesses, on this sixth day of August A. D. 1906.

LOUIS CARLETON BULKLEY.
